UNITED STATES PATENT OFFICE.

CHARLES T. THOMPSON AND RICHARD H. SANDERS, OF PHILADELPHIA,
PENNSYLVANIA.

MAGNETIC ORE-SEPARATOR.

SPECIFICATION forming part of Letters Patent No. 470,456, dated March 8, 1892.

Application filed December 5, 1891. Serial No. 414,137. (No model.)

To all whom it may concern:

Be it known that we, CHARLES T. THOMPSON and RICHARD H. SANDERS, both of Philadelphia, in the State of Pennsylvania, have invented certain new and useful Improvements in Magnetic Separators for Ore and Similar Material, whereof the following is a specification, reference being had to the accompanying drawings.

10 In said drawings, Figure 1 represents an end elevation of the separator; Fig. 2, a front view thereof; Fig. 3, a longitudinal vertical section on the lines $x x' x^2 x^3$; and Fig. 4 is a diagrammatic view illustrating the arrangement of the electro-magnets.

Our present invention is an improvement upon the apparatus specified in our application filed April 16, 1891, Serial No. 389,166.

The general description of the separator 20 to which our present invention applies, and which is broadly claimed in our said application is as follows: A hollow rotatable drum is combined with a stationary magnet placed exterior thereto and having poles which 25 closely embrace a portion of the exterior periphery thereof, the wall or shell of the drum being of such character and the magnet of such energy as to insure the projection of a magnetic field into a portion of the interior 30 of the drum. Stationary discharge-chutes are arranged within the drum beneath the upper limit of the magnetic field and lead from different parts thereof to points exterior to the drum. The material to be treated 35 is fed in at one end of the drum and caused to travel, preferably by gravity, toward the other end as the drum rotates. During such travel those portions of the ore or other material which are susceptible to magnetic action are attracted outward toward the magnetic poles, and are thereby held against the inner surface of the drum, rising with it in rotation until they reach the upper limit of the magnetic field, which overhangs the chutes. 40 As soon as that portion of the drum against which they have been held moves past said limit, they drop off from the inner surface of the shell into the chutes and are removed, preferably by gravity, to any desired receptacles.

The present improvements relate to the construction and arrangement of the magnets which are combined with the drum.

In the drawings, A represents a rectangular frame-work, preferably inclined or tilted as a whole upon its supports B.

C represents the separating-drum, rotatably mounted within the frame in the following manner: Around the periphery of the drum at one end is a projecting annular flange D, 60 having half-shrouded radial teeth d, which engage with the similarly half-shrouded teeth of a pinion D', mounted upon the driving-shaft F. Guide-rollers E, mounted upon the frame A and having peripheral grooves adapted to receive the projecting portions of the teeth d, are arranged in contact with the flange D at diametrical points, as shown particularly in Fig. 1. At the other end of the drum an annular flange c extends around the periphery 70 and is received and guided by means of the flanged rollers E' E² E³. The drum is thus freely supported for rotation; but endwise movement is prevented by the engagement of the grooved rollers with the flange c and 75 the toothed portion of the flange D. An inlet-chute M for the ore or other material leads into the upper or receiving end of the drum. The wall or shell of the drum should of course be of such a character as not to substantially 80 interfere with the formation of a magnetic field throughout a portion of its interior by the stationary exterior magnet. We prefer to employ non-magnetizable material—such as wood or brass—for the purpose, because 85 we are thereby enabled to use a magnet of less energy than where the wall is of magnetizable material; but we do not limit ourselves to the use of any particular material, it being only necessary that the magnet should be of 90 sufficient energy to project a substantial number of lines of force through the wall and thus form an efficient field within the drum. When, therefore, we use in our claim the term "substantially non-interfering" to describe the nature of this wall, we do not thereby prescribe the particular material of which the drum is to be constructed, but mean that it is of such character with reference to the 95 energy of the exterior magnet as to be inca- 100

pable of retaining within itself or cutting off the whole of the lines of force which that magnet is capable of projecting.

Along that side of the drum which is to the right in Fig. 1, and which for convenience we term the "front," are grouped the stationary electro-magnets, whose fields embrace, preferably, a semicircle of a vertical diameter. These magnets in the instance shown are three in number and each of them consists of a pair of parallel U-shaped plates with their inner edges facing the exterior of the drum, their entire outer edges being backed and connected by means of a flat U-shaped band, so that the cross-section of the plates and the connecting-band is also U-shaped.

In Fig. 3, L represents the backing or connecting band, and T t the plates at that magnet which is nearest to the receiving end of the separator, and which we term the "first" magnet. L' represents the band, and T' t' the plates, of the central magnet, and L², T², and t^2 represent, respectively, the band and the plates, of the magnet which is nearest to the discharging end, which we term the "last" magnet. The three magnets are held in position by bolts a' , a^2 , and a^3 , which pass through the transverse strips A', A², and A³, respectively, and are secured to the bands L, L', and L² of the respective magnets. The energizing coils of these magnets are wrapped around each of the plates lengthwise and follow the U-shaped contour thereof, exposing only the inner edge of the plate. Each magnet is therefore a shallow but very wide horseshoe, whose respective poles are U-shaped, extending the whole length of the inner edge of each plate.

To permit of variation in the energy of the different magnets, for the purposes which will be hereinafter described, we divide the coils of the first magnet into five groups, as shown in the diagrammatic view of Fig. 4, where N represents that group which is nearest to the pole or inner edge of the plate T; N', the next group; N², the third group; N³, the fourth group, and N⁴; the fifth group, or the one most remote from that pole. The other plate or leg t of the magnet is provided with similar groups n^5 , n^6 , n^7 , n^8 , and n^9 , which corresponds in position and number of coils with the respective groups upon the leg T.

The coils upon the central magnet are divided into four groups, those upon the plate T' being represented by P, P', P², and P³, respectively, while those upon the other plate t' are represented by p, p', p², and p³, respectively. The last magnet has its coils divided into three groups, those of the plate T² being indicated by Q, Q', Q², and Q³, while the corresponding ones upon the plate t^2 are indicated by q, q', and q².

The groups upon each magnet are, in the instance shown, connected in series, as are also the three electro-magnets themselves, and in order to permit the throwing into or out of circuit any desired number of the groups upon the respective magnets independent terminal

wires lead to the main wire at points intermediate between the several groups. These intermediate terminals for the coils of the first magnet are indicated by u, u', u², and u³, while the main terminals thereof are indicated by U and U'.

By means of a switch O, adapted to connect with any one of the respective terminal wires of the first magnet, the circuit can be limited to any desired number of the groups upon the said magnet, since the group or groups beyond the contact-point to which the switch is applied are of course cut out.

The main terminals of the central magnet are indicated by V V', the intermediate terminals by v v', v², and the switch by O'.

The main terminals of the third or last magnet are indicated by W W', the intermediate ones by w w', and the switch by O².

The source of electricity is indicated at O⁴. The current may be either direct or alternating.

The circuit-wires are respectively indicated at O³ and O⁵.

The capacity for variation of magnetic energy is greatest in the first magnet and least in the last magnet, the capacity of the central magnet for variation being intermediate between the two. We prefer, also, that when all three of the magnets are energized to their fullest extent, the last magnet should be the most powerful, the central magnet next in power, and the first magnet the one of least power.

Within the drum C are three delivery-chutes K, K', and K², arranged at different levels, but in line with the upper limit of the magnetic fields and leading, as shown in Fig. 3, from different longitudinal points. The chute K extends from the receiving end of the drum entirely to the delivery end. The chute K' extends from a point intermediate between the first and second magnets and leads out to the delivery end, overhanging, of course, the corresponding portion of the chute K, while the chute K² extends from a point intermediate between the second and third magnets to the delivery end and overhangs a corresponding portion of the chute K'. Thus the ores or other materials which drop from the drum at the upper limit of the magnetic fields are segregated in accordance with the field from which they fall, the purpose of such division being to effect a graded separation capable of variation through the control established over the respective magnets. Thus if the first magnet has one or more of the groups of its coils cut out of circuit, so as to reduce the energy of its field, only the richest ore will be held within this field and fall into the chute K. If the central magnet be energized to a degree intermediate between the first and last magnets, ore of the next degree of richness (or not sufficiently susceptible to have been arrested by the first magnet) will be retained in the central portion of the drum and will fall into the chute K'.

The third

magnet, which is energized to the fullest extent, should be sufficiently powerful to arrest all the remaining poorer portions of the ore and to insure their discharge into the chute K².

5 In the system illustrated in the accompanying drawings we have represented a very complete embodiment of our invention, in that the coils of each of the three magnets are divided into groups, as above described, so as to present a very wide range of possible variation; but it must be understood that we do not limit ourselves to the particular arrangement shown, since other and equivalent methods for varying the energy in the different fields may 10 be resorted to for the same purpose and with a like result—such, for instance, as employing separate sources of electricity for the three magnets and varying the currents thereof, or, in fact, employing any of the well-known devices whereby fields of different energy may 15 20

be produced. Furthermore, the members of the magnets may be course be increased or diminished to give the desired number of grades.

Having thus described our invention, we 25 claim—

The combination of a rotating drum having a substantially non-interfering wall, with a plurality of stationary electro-magnets, a plurality of chutes respectively extending from beneath the upper limits of the several fields to different delivery-points, and means, substantially as set forth, whereby the energy of the fields of one or more of the magnets may be varied, as and for the purposes specified. 30 35
